JARRING MACHINE

Filed Dec. 12, 1929

FIG. 2.

FIG. 1.

WITNESS:

Robt. R. Kitchel.

Frank R. Wallace

BY

Augustus B. Stoughton

ATTORNEY

UNITED STATES PATENT OFFICE

FRANK R. WALLACE, OF PHILADELPHIA, PENNSYLVANIA, ASSIGNOR TO THE TABOR MANUFACTURING COMPANY, OF PHILADELPHIA, PENNSYLVANIA, A CORPORATION OF PENNSYLVANIA

JARRING MACHINE

Application filed December 12, 1929. Serial No. 413,435.

My invention relates to jarring machines. These machines consist of a jarring table which is actuated by a jarring piston connected thereto. The jarring table is adapted 5 to carry flasks in which the molds are formed. These flasks are often placed so that the load on the jarring table is not central. One edge of the jarring table, therefore, tends to strike the base before the other edge. This puts a 10 side blow on the piston which in time causes it to tear out the bolts which connect the piston and the table or to break off the piston or sometimes the cylinder in which it moves or sometimes even the jarring table itself. 15 My invention consists in providing a connection between the jarring table and the piston which permits of sufficient flexibility to eliminate such breakage.

For a further description of my invention 20 reference may be had to the annexed drawings and specification at the end whereof my invention will be specifically pointed out and claimed.

In the drawings, 25 Figure 1 represents a vertical cross section through my device, and

Figure 2 is a vertical cross section drawn to an enlarged scale and showing in detail the bolts and connecting elements.

30 Referring to the drawings, There is shown a jar ramming molding machine consisting of a foundation 1 on which rests a base 2. Cooperating with the base is a jarring table 3 having attached thereto a piston 4. Attached to base 2 is a cylinder 5 within which the jarring piston rides. The piston 4 is fluid operated by pressure introduced through pipe 6 and valve mechanism 7. This causes piston 4 to carry 35 table 3 and the flasks carried thereby upward and then permits them to drop so that table 3 strikes base 2 at the marginal portions or ribs thereof with a sharp blow.

Referring now more especially to Figure 45 2, there is shown a construction in which table 3 is connected to piston 4. Piston 4 is formed with a flange 8 having a series of holes therein. Table 3 has a flange 9 having tapped holes therein and adapted to come 50 opposite the holes in flange 8. Bolts 10 pass

through the holes in flange 8 into the tapped holes in flange 9 and thereby fasten table 3 to piston 4. The bolts 10 have their ends riveted over against table 3 as indicated at 11.

A flexible connection or coupling between 55 table 3 and piston 4 is provided by inserting disks 12 and 13, which may also be of any other suitable shape, between flange 8 and flange 9 and between flange 8 and plate 14 which is carried beneath the heads of bolts 60 10. The disks 12 and 13 may be of rubber or any other resilient material but as a preferred example I use ebonite oil proof rubber. Surrounding each of the screws 10 is a metallic sleeve 15 which is interposed between 65 the screws and the elements 12 and 13.

In assembling my device, the bolts 10 clamp 70 plate 14 securely against sleeve 15 which in turn bears upon flange 9. The elements 12 and 13 are slightly compressed by this clamping action and thereby permit the flange 9 to move relative to flange 8, an amount equal to the compression of the washers 12 and 13. An attempt has been made to illustrate upon the drawing any slight clearance that is necessary to permit of the described relative movement in the nature of universal movement but the clearance is exaggerated and the wobbly movement though exceedingly small is sufficient to relieve excessive strain of table 3 on piston 4 and to thereby eliminate much breakage of piston 4 or pulling of bolts 10. 75

In further explanation it may be said that if the load on the table 3 is unbalanced, for example, heavier on the lefthand side of the table, the lefthand striking surface will strike slightly in advance, in point of time, than the righthand striking surface. There will, therefore, be a slight turning movement of the table into horizontal position, but since the connection between the piston and table is flexible, the piston is free to adjust itself through slight vertical movement and there is no side blow on the piston. 80

It will be obvious to those skilled in the art 85 to which the invention relates that modifications may be made in details of construction and arrangement and matters of mere form without departing from the spirit of the invention which is not limited to such mat- 90 100

ters or otherwise than the prior art and the appended claims may require.

I claim:

1. A jarring machine comprising a piston,
5 a jarring table, bolts connecting said piston
and said table, and compression members in-
terposed between said piston and said table.
2. In a jar ramming molding machine the
combination of a base and a table having pro-
10 vided between them a marginally arranged
horizontal striking surface, a cylinder pro-
vided on the base and disposed substantially
centrally of the table, a piston arranged for
vertical reciprocation in the cylinder, over-
15 lapping flanges provided on the table and pis-
ton, and a yielding medium interposed be-
tween said flanges and providing a flexible
coupling adapted to permit the piston to con-
tinue to move vertically when one side of the
20 table under unbalanced load strikes a blow
in advance on a portion of the striking sur-
face whereby breakage is prevented.
